UNITED STATES PATENT OFFICE.

THOMAS H. LOY, OF TERRE HAUTE, INDIANA.

BRAKE MECHANISM FOR TALKING-MACHINES.

1,349,216.

Specification of Letters Patent. Patented Aug. 10, 1920.

Application filed January 10, 1917. Serial No. 141,633.

To all whom it may concern:

Be it known that I, THOMAS H. Loy, a citizen of the United States, residing at Terre Haute, in the county of Vigo and State of Indiana, have invented certain new and useful Improvements in Brake Mechanisms for Talking-Machines, of which the following is a specification.

The present invention relates to improvements in automatic brake mechanisms for talking machines in which the brake member is arranged for stopping the rotation of the revoluble record support at a desired time under the control of a traveling member, whether the latter be the reproducer arm itself or an element operable in correspondence therewith.

The primary object is to provide a device of this character capable of being adjusted so as to enable the stopping of the machine at a predetermined time preferably when the reproducer of the traveling member has reached the desired position on the record corresponding to the termination of the sound being reproduced.

Another object in view is to provide for ready adjustment of certain of the coöperating parts of the mechanism whereby the same may be readily adapted to different styles of well known talking machines and the point of application of the brake may be determined with precision.

It is further comprehended as of the essence of my invention to provide indicating means for obtaining a proper setting of the mechanism for actuation of the brake as predetermined by certain indicia associated with the record itself and signifying substantially that point in the sound groove of the record where the rendition of the sound ceases.

To this end the invention consists of brake mechanism including a locking member for holding the brake in retracted position and adjustable releasing means operable synchronously with the reproducer for actuating said brake mechanism to effect a release or application of the brake.

For a full understanding of the present invention, reference is to be had to the following description and the accompanying drawings, in which:

Figure 1 is a top plan view of a talking machine having the preferred embodiment of my invention attached thereto, certain

parts of said machine being broken away to disclose the details of construction of the device and showing the brake mechanism in retracted position coöperative with the revoluble record support rendering the latter inoperative.

Fig. 2 is a transverse sectional view on the plane indicated by the line 2—2 of Fig. 1.

Fig. 3 is an enlarged plan view of the subject-matter of this invention showing in full lines the position assumed by the parts preliminary to release of the brake member which has been previously set and in dotted lines the coaction of the releasing means with the locking member for the brake to produce application of the latter for stopping the record support.

Fig. 4 is a detail view of the locking member for the brake.

Fig. 5 is a detail view of the brake member.

Fig. 6 shows a plan view of a gage that may be used for determining the point upon different records which are not previously provided with indicia for application of the brake action whereby the adjusting means of the releasing mechanism may be properly adjusted for use.

Fig. 7 is an enlarged detail view of the adjusting stop for the pawl of the brake member.

Throughout the following detail description, and on the several figures of the drawings, similar parts are referred to by like reference characters.

Referring to the drawings, 1 designates a casing of a talking machine of conventional form in which is contained the driving mechanism for rotating the record support 2 mounted upon the revolving spindle 3 and embodying the reproducer or tone arm 4 carrying the reproducer 5 and pivotally mounted interiorly of the casing upon the vertical shaft 6 extending above the surface of the casing. The shaft 6, it may be stated, revolves through the instrumentality of operative connections with the reproducer arm and is provided with a cam or lever 7 which is capable of being raised so as to establish proper connection for actuating the reproducer arm when its reproducer is coöperating with the sound record in reproducing the sounds therefrom, but when said lever is lowered as in Fig. 1 the reproducer arm is free to be moved manually into inoperative relation with respect to the record support to

85

enable the record to be displaced and for other objects to be understood as this description proceeds.

- As my invention, which is now to be described, is capable of adaptation to different forms of talking machines, I do not wish to be confined to the illustrated embodiment just described. My invention comprises essentially what, for the purposes of this description, may be termed two essential elements, namely the brake mechanism, generally indicated by the character A and the releasing means therefor, generally indicated by the character B.
- 10 The brake mechanism consists of the brake member 9 which is pivotally mounted on the surface of the casing 1 as indicated at 10, beneath the record support 2 in position for its friction device or shoe 11 to coöperate with the flanged periphery of said support. Coöoperating with this brake member is a locking member or latch 12 which is pivotally mounted on the casing 1 adjacent to the pivot 10, as indicated at 13 and said locking member is provided with an opening 14 substantially centrally thereof in which a downwardly bent flange 15 of the brake member 9 projects. It will be noted that the opening 14 is formed with a lateral offset to provide a shoulder 16 with which the flange 15 is adapted to engage when the brake member is actuated to move it into retracted position, so that the locking member 12 will hold said brake member in such position.
- 15 The end of the brake member 9 opposite to that carrying the brake shoe 11 has connected thereto a spring 17, the other end of which is connected to the locking member 12 adjacent to its pivot preferably. This spring performs an important function in that it tends to draw the locking member into position for establishing the locking co-operation of the brake member and the shoulder 16, and furthermore it constitutes the actuating means for said brake member whereby the latter when released has imparted thereto pivotal movement shifting the brake shoe into contact with the rotatable support, thus applying brake action.
- 20 The latch 12 is formed with an extension which projects beyond the periphery of the rotatable support 2 as indicated at 12' and said extension carries an adjustable trip plate 18 which is secured to the upturned extremity of said extension by means of the fastening screw 19. As will be observed in Fig. 4, the upturned extremity of the extension 12' is slotted so that the screw 19 may be shifted transversely of the extension 25 to thereby adjust the projection of the trip plate 18 for the purposes hereinafter set forth.

Reverting to the construction of the brake member 9 it will be observed that said member carries thereon a pawl 20 pivotally se-

cured at 21, said pawl having a stop arm 22 adapted to be held against the adjustable stop 24 by means of the spring 23. Said spring normally holds the opposite setting arm 25 of the pawl in normal operative position in the path of movement of the releasing device B by means of the coaction of which the brake member 9 is set in inoperative position.

Referring now to this releasing device B, 75 it will be observed that the same consists preferably of a plate 26 which is fixedly mounted upon the shaft 6 for rotation therewith synchronously with the rotation of the reproducer arm 4. The plate has connected thereto an arm 27 terminating in a flanged extremity 28 which in the rotation of said plate 26 impinges the setting arm 25 of the pawl 20. This arm 27 is adjustably secured by means of the fastening member 29 beneath the plate and said fastening member also is common to an adjusting member 30. The latter at its inner end has a lateral extension 31 which is arranged to impinge the trip plate 18 of the locking extension 12', when the releasing device B revolves to bring these elements into coöperation. The other end portion of the adjusting member 30 constitutes an indicating pointer 32 which is provided with a knob 33 whereby said pointer may be shifted about its pivot on the plate 26 which bears at its outer peripheral portion certain indicia designated 34. These indicia may be of an arbitrary character involving numerals and a series of lines, all of which bear a certain coöperative relation to the point which represents the termination of the sound which is to be reproduced from the record as said point may vary in different sized records or records of different lengths.

Assuming for the moment preliminary to the general description of the operation that the operator is advised by indicia which is carried by the record or elsewhere that the point where the brake is to be released for application of the particular record which is to be played is determined by a numeral "34" or its equivalent. The operator would adjust the pointer to a corresponding numeral on the plate 26 and the brake mechanism would be in adjustment for proper operation at the predetermined time.

It may be explained that the most convenient method of securing proper adjustment of this mechanism is by applying some indicia to the record either at the time of manufacture or subsequently thereto such indicia being determined upon by experimental tests of the termination of the reproduction for it only necessitates under such condition the simple adjustment of the indicating pointer 32 to indicia on the plate 26 which corresponds thereto. Inasmuch, however, as this mechanism is designed to 130

be applied to machines of this general type, the mechanism is made adjustable so that there will be a proper correspondence between the indicia on the record and the indicia on the indicator 26. For example, when the locking member 12 has been secured in operative position upon the talking machine case, and it is desired to accomplish the proper adjustment of the parts with precision, the operator will take a record which bears any predetermined symbol, such as indicated in Fig. 1, and will place said record upon the turn table 2, setting the indicator 32 on the corresponding symbol or indicia of the plate 26. The last part of the record is now played and if the machine does not stop automatically soon enough to suit, the screw 19 of the locking plate extension is loosened and the plate 18 moved toward the releasing mechanism or arm 31; if the machine stops too soon this slide is adjusted in the opposite direction. Once the adjustment has been properly obtained there will be a correspondence between the indicia which is carried by the record or elsewhere, and the indicia on the indicator 26, where the former has been determined upon by the same method, for all records.

Describing the operation of the mechanism, assuming the foregoing adjustment to have been properly established and the indicator of the releasing means has been set, the reproducer arm is moved inwardly thus 35 rotating the shaft 6 and carrying therewith the indicator until the setting arm 27 impinges the projecting arm of the pawl 20 lying in its path; further movement rotates the brake member 9 about its pivot and 40 causes the flange 15 to slide on the edge of the opening 14, placing the spring 17 under increased tension until the offset of said opening is reached whereupon the locking member will be moved about its pivot and 45 the flange engaged with the shoulder 16 of said locking member. The brake is thus retracted and the reproducer arm is now set down upon the outer peripheral portion of the record for reproduction, the lever or 50 cam 7 having been raised to establish operative connection of the reproducer arm with the driving mechanism of the talking machine. The release device B will now be rotated again about its pivot with the shaft 55 6 during the reproduction of the sound record until the reproducer reaches the end of the reproduction whereupon the arm 31 of the indicator will impinge the trip plate 18 of the extension 12' and cause the locking member 12 to be moved laterally, thus 60 disengaging the flange 15 from the shoulder 16, allowing the setting of the brake which immediately coacts with the record support to cause the latter to stop its rotation. Owing to the fact that the pawl 20 is one-way-

acting only, the indicator will move readily back to its inoperative position along with the reproducer arm when the driving connection therewith has been disestablished through the instrumentality of the cam 7 70 as hereinbefore described.

It will be observed from the foregoing description that the setting of the brake in its retracted position moves this member into a position out of operative relation to 75 the setting arm 27 so that the latter will pass freely by the end of the pawl 20 and in this manner the locking member 12 is rendered operative by the release means B.

The method of adjusting the automatic 80 starting of the record support is as follows:

Place the reproducer at the farthest position from the center of the record, in doing which the setting arm 27 will pass the projecting arm of the pawl 20 which yields 85 under action of its spring, then move the reproducer toward the center of the turn table slowly. If the flange 15 cramps against the farthest edge of the opening 14, the adjusting stop 24 should be utilized so as 90 to change the position of the arm 22 of the pawl disposed thereagainst. This stop is rotated to effect this adjustment and in the event the flange 15 does not engage properly with the shoulder 16 the same adjusting stop 95 24 may be adjusted to overcome this defect. Furthermore if the setting arm 27 is not in proper position for coöperation with the arm 25 of the pawl 20, the fastening screw 29 may be loosened, and said arm 25 ad- 100 justed about its pivot into proper position whereupon the said fastening means is tightened. The foregoing adjustment of the parts makes possible the readjustment 105 to compensate for the wear on the friction piece 11 incidental to the use of the machine.

In Fig. 6, I have shown a means for determining the indicia which is to be applied to different records in order to facilitate the use of the braking mechanism which is hereinbefore described. Said means consists merely of a gage plate 35 having an angularly bent fingerpiece 36. This plate is provided with certain indicia 37. By placing the end of the gage plate at the opening of the record and observing the point of the scale on this gage which lies at the innermost sound groove of this record, the proper designation for that particular record is determined. In the illustration, for instance, the numeral 1 represents approximately the end of the sound groove and said record is suitably designated with the corresponding symbol by means of a pasteur 110 38 or otherwise. It will be apparent to those skilled in the art to which this invention refers that various other means may be employed for arriving at the same result.

It may here be observed that the use in the claims of the terms "turn table" and 130

"reproducer or tone arm" is in their generic sense and not in their limited sense. Various changes may be readily made in the details of construction of this device without departing from the spirit of the invention, and within the scope of the appended claims.

Having thus described my invention, what I claim as new is:

- 10 1. In brake mechanism for graphophones or the like, the combination with a turn table and a reproducer arm movable relatively thereto, of braking means including means for holding the same in brake applied and retracted positions with respect to the turn table, and release means operable coincident with the initial movement of the reproducer arm to playing position and engageable with said braking means to retract the same upon movement of the reproducer arm a predetermined extent in one direction, said release means being arranged to cause the braking means to be applied while the reproducer arm continues moving 25 in its playing operation whereby to stop the turn table upon a greater degree of movement of the arm in the same direction as aforesaid.
- 20 2. In brake mechanism for graphophones or the like, the combination with a turn table and a reproducer arm adapted to traverse said table in sound reproduction operation, of braking means, a locking member therefor including means for holding it in locking position, and means separate from said locking and braking means operable coincident with initial movement of the reproducer arm to playing position to engage and thereby retract the brake and effect an interlocking engagement of the locking member with the brake, said locking member being thus rendered operable subsequently by said separate means to affect application of the braking means while the reproducer arm continues moving in its playing operation.
- 30 3. In brake mechanism for graphophones or the like, the combination with a turn table and a reproducer arm adapted to traverse said table in sound reproduction operation, of a brake, adjustable actuating means to retract the brake operable coincident with the movement of the reproducer arm inwardly to playing position, and means for retaining the brake in retracted position when the brake has been actuated as aforesaid, said holding means being disposed preliminary to the actuation in inoperative position with respect to the actuating means but rendered operative by said actuating means when once the brake has been shifted into the retracted position aforesaid whereby said holding means may be disengaged from the brake to apply the

same at a predetermined point in the movement of the reproducer arm. 65

4. In brake mechanism for graphophones or the like, the combination with a turn table and a member movable relatively thereto, of brake mechanism including a 70 brake member arranged to be impinged by and upon the initial movement of the movable member into playing position to retract the brake, and holding means for retaining the brake at such position and in 75 inoperative relation out of the path of said movable member whereby to permit the latter to freely pass thereby for subsequent actuation of the holding means by the movable member to apply the brake while the 80 movable member continues moving in the playing operation.

5. In a device of the class described, the combination with a turn table and a reproducer arm movable relatively thereto, of 85 brake mechanism including a brake member, a locking member for holding said brake in retracted position, and means operable coincident with the movement of the reproducer arm inwardly to reproduction 90 commencement position to preliminarily position the brake automatically by contact therewith in retracted position and subsequently to actuate the locking member to effect disengagement thereof and application of the brake while the reproducer arm continues moving in its playing operation. 95

6. In a device of the class described, the combination with a turn table and a reproducer arm adapted to traverse a record 100 supported thereon, of actuating means operable with the reproducer arm in sound reproduction operation, brake mechanism including a brake member normally arranged in the path of movement of the actuating 105 means, said brake member being displaceable by the actuating means upon manual operation of the reproducer arm inwardly into playing position to thereby retract the brake, holding means also arranged in the path of movement of the actuating means and adapted to hold the brake member in retracted position permitting impingement of the actuating means upon continuation of traverse of the reproducer arm to effect disengagement of the holding means and application of the brake at a predetermined time. 110

7. In a device of the class described, the combination with a turn table and reproducer arm adapted to traverse a record supported thereon, of brake mechanism including a brake member, a locking member for holding said brake member in retracted position, retracting means operable as an incident to movement of the reproducer arm inwardly into playing position to preliminarily automatically retract the brake and 115 120 125

subsequently actuate the locking member to effect application of said brake, said means carrying trip means adjustable thereon to vary the operation of said locking member for applying the brake at predetermined times.

8. In a device of the class described, the combination with a turn table and reproducer arm movable relatively thereto, of brake mechanism including a brake member, a locking member for holding said brake member in retracted position, release means arranged to preliminarily automatically retract the brake member incident to

10 inward movement of the arm to playing position for commencement of reproduction operation and subsequently actuate the locking member to apply the brake at a predetermined time, and means for adjusting the 15 release means to effect variation of coöperation thereof with the locking member to control the time of applying the brake according to reproduction termination.

9. In a device of the class described, the 20 combination with a turn table and a reproducer arm movable relative thereto, of brake mechanism including a brake member, a locking member for holding said brake member in retracted position, release means 25 operable with the arm arranged to preliminarily retract the brake by an inward movement to playing position and subsequently to actuate the locking member to effect application of the brake, adjustable means 30 operating with the release means whereby to effect retraction of the brake member at a predetermined point in the movement of the arm, and auxiliary adjusting means for regulating the retraction of the brake.

40 10. In a device of the class described, the combination with a turn table and a reproducer arm adapted to traverse a record supported thereon, a brake mechanism including a brake member, holding means for 45 holding the brake member in retracted position, an indicator device constituting means for retracting and applying the brake member, said means being operative during initial movement of the reproducer arm in 50 the direction to set the same in playing position whereby to retract the brake, and upon further movement in this same direction to effect application of the brake, said device including an indicator adjustable to 55 predetermine at will the time during travel of the arm as aforesaid of coöperation of the retracting means with said holding means.

11. In a device of the class described, the 60 combination with a turn table and a reproducer arm movable relatively thereto, of brake mechanism including a brake member coöoperative with the turn table, holding means for holding the brake member in retracted position, an indicator device includ- 65 ing a brake retracting arm arranged to move

the brake into retracted position as an incident to movement of the reproducer arm for sound reproduction and thereby rendering said holding means accessible for operation by the indicator device, and means 70 carried by the indicator device arranged to impinge the holding means after the brake is retracted as aforesaid whereby to effect application of the brake at a predetermined time.

12. In a device of the class described, the combination with a turn table and a reproducer arm movable relatively thereto, of brake mechanism including a brake member coöoperative with the turn table, holding 80 means for holding the brake member in retracted position, an indicator device including a brake retracting arm arranged to set the brake in retracted position during the initial travel of the reproducer arm to playing 85 position and rendering said holding means subsequently operative by the indicator device, and means coöoperative with the indicator device arranged to actuate the holding means when the brake is in retracted position, whereby to effect application of the brake at a predetermined time, said last mentioned means constituting an adjustable pointer for predetermining the coöperation of the indicator device with 95 said holding means.

13. In a device of the class described, the combination with a turn table and a reproducer arm movable relatively thereto and including an operating shaft, of brake 100 mechanism comprising a brake member and a locking member for holding the brake in retracted position, means for retracting said brake member comprising a plate carried by the operating shaft aforesaid and bearing 105 indicia, an indicator pointer adjustably carried by said plate to indicate the point in the travel of the reproducer arm desired for application of the brake, said pointer having an extension arranged to retract and 110 subsequently freely pass the brake when the latter is retracted to coöperate with the locking member to effect release of the same and application of the brake.

14. In a device of the class described, the 115 combination with a turn table and a reproducer arm movable relatively thereto and including an operating shaft, of brake mechanism comprising a brake member and a locking member for holding the brake in 120 retracted position, means for retracting said brake member comprising a plate carried by the shaft aforesaid and bearing indicia, an indicator pointer adjustably carried by said plate to indicate the point in the travel 125 of the reproducer arm desired for application of the brake, said pointer having an extension arranged to coöperate with the locking member to effect release of the same and application of the brake, and a brake 130

retracting arm carried by said plate arranged to coact with the brake member to set the same in retracted position prior to engagement of the extension with the locking member as aforesaid.

15. In a device of the class described, the combination with a turn table and a reproducer arm movable relatively thereto and including an operating shaft, of brake mechanism comprising a brake member and a locking member for holding the brake in retracted position, means for retracting said brake member comprising a plate carried by the operating shaft aforesaid and bearing indicia, an indicator pointer adjustably carried by said plate to indicate the point in the travel of the reproducer arm desired for application of the brake, said pointer having an extension arranged to coöperate with the locking member to effect release of the same and application of the brake, a brake retracting arm carried by said plate arranged to coact with the brake member to move the same into retracted position prior to engagement of the locking member as aforesaid, and means for adjusting the retracting arm to regulate the displacement of the brake member thereof.

16. In a device of the class described, the combination with a turn table and a reproducer arm, brake mechanism including a brake member and a locking member therefor, of pivoted release means operated by said reproducer arm to render said means effective for actuation of the locking member, said means including an adjustable element adapted to coöperate with the locking member and movable in opposite directions to increase or decrease the arc of movement of the release means requisite to effect engagement of the latter with the locking member, and means disposed to retract the brake upon initial movement of the reproducer arm to playing position.

45 17. In stop mechanism for sound reproducing instruments the combination of a pivoted brake member, a locking member arranged in coöperative relation to said brake member, tension means for said locking member, said locking member having a shoulder with which the brake member is engageable to hold the latter in retracted position, and release means operable during initial movement of the reproducer arm toward the axis of the turn table for sound reproduction to impinge the brake member to retract the same from the turn table, and including means for actuating the locking member upon continued sound reproducing movement to disengage said brake member from the shoulder aforesaid and thereby effect application

of the brake while the reproducer arm continues moving in its playing operation.

18. In stop mechanism for sound reproducing instruments the combination with a 65 brake member having a flange, an arm mounted on said brake member for effecting actuation thereof, a locking member arranged adjacent to the brake member and having an opening therein to receive the 70 brake flange, said opening having an offset forming a shoulder with which the flange is adapted to engage, tension means intermediate said brake and locking members, and release means adapted to engage the 75 brake arm to move said brake member into engagement with the shoulder when the reproducer arm is initially moved to playing position, said releasing means being adapted to engage the locking member for effecting 80 release of the brake from said shoulder.

19. In stop mechanism for sound reproducing instruments the combination of a 85 brake member, a one way acting abutment arm movably mounted thereon, a locking member arranged to coöperate with the brake member for holding the same in retracted position, and release means engageable with the arm to set the brake in the said retracted position and including separate means for actuating the locking member after said brake has been actuated, to effect application of the said brake.

20. In stop mechanism for sound reproducing instruments the combination of a 95 brake member, a spring actuated pawl carried thereby, means for adjusting said pawl with respect to the brake member, means for holding the brake member in retracted position, and means to actuate the brake member through the pawl to retracted position and by further movement to actuate the holding means to effect application of the 100 brake.

21. In stop mechanism for sound reproducing instruments the combination of a 105 brake member, a spring actuated pawl carried thereby, an adjustable stop member coacting with said pawl for effecting adjustment thereof, a locking member for holding 110 said brake member in retracted position and having an interlocking connection therewith, tension means for said brake and locking members, a trip element adjustably carried by said locking member, and release means comprising a brake retracting arm adapted to coöperate with the pawl aforesaid, and adjusting means coöperative with the trip means when said brake is in retracted position.

In testimony whereof I affix my signature.
THOMAS H. LOY.
